UNITED STATES PATENT OFFICE.

P. P. STEWART, OF TROY, NEW YORK.

COOKING-STOVE.

Specification forming part of Letters Patent No. 22,681, dated January 18, 1859; Reissued May 31, 1864, No. 1,684.

To all whom it may concern:

Be it known that I, P. P. STEWART, of Troy, in the State of New York, have invented certain new and useful Improvements in Cooking-Stoves, of which the following is a full, clear, and exact description, reference being had to the accompanying drawings, making part of this specification, in which—

10 Figure 1, is a side elevation. Fig. 2, a front elevation. Fig. 3, a longitudinal vertical section; and Figs. 4, 5 and 6, sections taken at the lines A, a, B, b, and C, c, of Fig. 1.

15 The same letters indicate like parts in all the figures.

My said invention relates to improvements on what is known as the return flue cooking stove, in which the products of combustion pass over the oven in one sheet, divide and pass down the back in two flues, thence under the bottom in two flues to the front, then turn the end of two partitions, unite and return in one middle flue to the back and up 25 the middle flue at the back to the exit pipe. In such stoves the outside, back and bottom plates which form one surface of the back and bottom flues radiate much heat into the room, an effect which is desirable in winter but very obnoxious in summer. Another defect of this class of stoves is that the heat radiated by the front of the stove is not sufficient for the purpose of roasting in a tin kitchen in front, the opening for fuel being 30 through a door at the side. And the third defect arises from the difficulty of keeping hot water for the reason that the fire chamber extends across the whole width, is placed near the front, and the plates surrounding 35 it form part of the top of the oven, the front, bottom and back plates thereof radiating heat into the oven, and in consequence the water heater, usually called the water back, cannot be used.

40 The object of my invention is to remedy the defects above pointed out while at the same time I retain all the known and admitted advantages of this class of stoves.

The back and bottom direct and return 50 flues, have a false and movable back and bottom plate which inclose the permanent back and bottom plates with an open space between them, that they may be put on in warm weather when but little fire is used

and it is desirable to prevent the radiation 55 of heat into the room, that the heat instead may be confined and thus made to act with more intensity upon the oven plates; and that they may be removed in cold weather when more fire is used and when it is desirable to warm the room. In this way the stove is adapted to summer and winter use, and made as efficient for the purposes of cooking in summer with a small, as in winter with a large amount of fuel. 60

The first part of my invention consists in combining with a stove of this class, doors in front and of sufficient capacity to place an open roasting kitchen, so that the heat radiated by all the plates and the back, front 65 and bottom plates of the fire chamber may be employed for roasting in front, when combined with an end door, whereby the draft may be controlled without the aid and independent of the front doors. And the 70 second part of my invention consists in arranging with such a stove a boiler at the back with two inclined flues, having a removable cover which receive the products of combustion separately at each side and from 75 a flue chamber in which the middle back flue discharges, and passing up obliquely in each unite at or near the top where the two flues unite to form the one connection with the pipe leading to the chimney. In this 80 way I am enabled to obtain an amount of heating surface sufficient to keep up the requisite supply of hot water, a result which has never before been obtained in stoves of 85 the kind specified. 90

In the accompanying drawings (a) represents the fire place in front and extending entirely across the front end of the stove; with a door (b) at one side for the supply of fuel. The front plate (c) of this fire 95 chamber is very near the front plate (d) of the stove, and the bottom plate (e) and back plate (f), and bottom plate (g) of the top flue (h) constitute the top of the oven (i). This oven has doors (j) at the sides for access, and a door (k) in front which extends up nearly to the top of the fire place, so that when this door is opened and a tin kitchen or roaster placed in front on the apron (l) the heat radiated by the several plates of the 100 oven will aid the heat radiated by the front plate of the fire chamber in roasting, while at the same time the heat will be confined in 105

the oven for the purposes of baking by the tin kitchen or roaster which for the time being closes up the front aperture.

The top flue (*h*) at the rear end opens directly into an exit flue chamber (*m*) through an aperture governed by a damper (*n*) which is opened to kindle the fire, or when it is not desired to heat the oven, but when closed then the top flue discharges into two diving side flues (*o*, *o*) at the back, and these discharge into two side flues (*p*, *p*) at the bottom, passing directly under the bottom plate of the oven. And at the front end of the oven these two flues (*p*, *p*) discharge into a return flue (*q*) placed between them and running back and discharging into a vertical flue (*r*) at the back and placed between the two diving or side flues (*o*, *o*) and the upper end of this discharges into the exit flue chamber (*m*). The back and bottom flues above described are made as usual in this class of stoves by the oven plates and back plates (*s*) and bottom plate (*t*) of the stove; and these are inclosed by a false back (*u*) and false bottom (*V*) whenever, as before stated, it is desired to prevent the heat from being radiated into the room. This false back (*u*) is made either of sheet or cast metal with the edges fitting close to the surface of the stove, and with a flaunch at top which enters under a cleat (*w*) on the under surface of the bottom plate (*x*) of the exit flue chamber (*m*) and then held in place at bottom by a pin (*y*) fitted to a hole in the bottom plate or by any well known catch; and the false bottom (*V*) has a rim all around, the upper edge of which fits up against the bottom plate of the stove, and it is provided with a lip (*z*) like a hasp, on each side which fits over a staple on the bottom plate of the stove that it may be secured in place by bolts or pins passing through the eyes of the staples. The false back and bottom are so formed as to leave an air space between them and the stove back that the air contained therein may act as a non-conductor to prevent the radiation of heat into the room.

The top plate (*a'*) of the stove extends back over the exit flue space (*m*) and besides the usual boiler holes it has a large hole (*b'*) to receive a large boiler (*c'*) formed with

two flues (*d'*, *d'*) which pass through the bottom, one near each side, and run up obliquely through and to the top of the boiler 55 where they unite in one, as at (*e'*), to connect with the usual stove pipe or chimney. As the gaseous products of combustion enter the flue space (*m*) from the middle back flue they must spread and act under the bottom of the boiler to get to the two flues in the bottom of the boiler, through which they ascend to the pipe. The boiler (*c'*), as is shown by the drawings, has a removable or hinged cover, thus allowing easy access to its 60 interior for the supply or removal of its contents and the making of it closed or tight; as occasion or use may require. In this way the heated gases not only act efficiently 65 against the entire bottom of the boiler, but 70 inside thereof through two flues which have their heating surface increased by being inclined to form the single connection with the chimney.

What I claim as my invention of improvements on the well known return flue stove herein specified, is—

1. In combination with a stove such as described making the front plate of the oven open with doors and an apron to receive and hold a tin kitchen or roaster, substantially as specified, that the heat radiated by the front plate of the fire chamber may be aided by the heat radiated by all the oven plates, as specified, when combined with an end 85 door, whereby the draft may be controlled without the aid and independent of the front doors.

2. And I also claim the boiler having a removable cover and two inclined flues 90 which are separate at the lower end and united into one at top to connect with the chimney, substantially as described, in arrangement with the exit flue space to which the boiler is fitted, and into which the gaseous products of combustion are discharged 95 from the series of direct and return flues, substantially as, and for the purpose specified.

P. P. STEWART.
